Attn:

UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

RADIATOR

Original application filed September 25, 1925, Serial No. 58,540. Divided and this application filed July 8, 1929. Serial No. 376,649.

This application is a division of my copending application Serial No. 58,540, filed Sept. 25, 1925 which has now matured into Patent #1,726,360.

5 My invention relates generally to radiators, and particularly to radiators of the type which may be advantageously employed in automobiles, aeroplanes and in general in the cooling of internal combustion engines and 10 the like.

The invention has among its various objects the production of devices of the kind described which are durable, efficient and satisfactory for use wherever found applicable.

15 A particular object of the invention is to provide improved radiator construction which will insure that substantially all of the air passing through the radiator will come in contact with the water tubes.

20 Many other objects and advantages of the construction herein shown and described will be obvious to those skilled in the art from the disclosure herein given.

To this end my invention consists in the 25 novel construction, arrangement and combination of parts herein shown and described, and more particularly pointed out in the claims.

In the drawings, wherein like reference 30 characters indicate like or corresponding parts:

Fig. 1 is a fragmentary view in elevation of a radiator embodying my invention;

Fig. 2 is a sectional view taken on the line 35 2-2 of Fig. 1;

Fig. 3 is a sectional view taken on the line 3-3 of Fig. 2;

Fig. 4 is a view similar to that of Fig. 2 showing another embodiment of my invention; and

Fig. 5 is a sectional view taken on the line 5-5 of Fig. 4.

Referring first to Figs. 1 to 3 inclusive, radiators comprising my invention embody 45 a plurality of relatively flat or elongated

tubes 10 which are mounted in plates 11, the plates being arranged in parallel spaced relation to each other transversely of said tubes. The plates 11 are provided with a plurality of apertures 12 for receiving the tubes. The plates 11 are preferably provided with annular flanges 13 which surround the apertures 12, and are designed to closely fit the tubes 10 when arranged in said apertures.

The tubes 10 are preferably soldered to the plates 11 and in practicing my improved method more fully described in my copending application Serial No. 58,542, filed Sept. 25, 1925, the plates 11 are first coated with any suitable substance to which solder will not 60 adhere. This coating is removed from the inside of the flanges by means of a wire brush or the like and the tubes and plates are then held in their assembled positions by any suitable temporary means (not shown) and are 65 dipped a short distance into a bath of fused solder so that the solder will flow along the flanges 13 and thus form a joint between the adjacent surfaces of the tubes and said flanges. The solder flows along the flanges 70 but does not adhere to the coated surfaces of the plates, nor those portions of the tubes disposed between the plates.

The plates 11 are provided with a plurality of rectangular angularly disposed deflectors 75 14 which are produced by being stamped or struck from the plates in such a manner as to produce apertures 15 in the plates providing air passages. The deflectors 14 are preferably disposed obliquely and at an angle to each other as shown in Fig. 2 so that they will direct the air and cause the air passing through the radiator to impinge, first one tube and then the other of adjacent pairs of tubes. It is evident that by providing the plates 11 with apertures and arranging the deflectors adjacent the apertures and disposing the deflectors so that they will direct the air toward said tubes that turbulence of the air between said plates and tubes is created which aug- 80 85 90 95

ments the cooling effect of the air upon these tubes. The embodiment of the invention shown in Figs. 4 and 5 substantially corresponds to the embodiment illustrated in Figs. 5 1 to 3, except that the deflectors 14a thereof are bent at an angle to the perpendicular, whereas the deflectors 14 of Figs. 1 to 3 are substantially perpendicular to the plane of the plate 11. From the foregoing description, it is manifest that the structure described provides means whereby air passing through the radiator is directed toward the water tubes thereof and that said air is during this passage turbulated, which thereby 10 augments the cooling effect of the air upon said tubes and furthermore, by the provision of the apertures in the cooling fins or plates of the structure that a portion of the air located between one pair of plates or fins is drawn 15 therefrom to between an adjacent pair of plates, thus increasing circulation of the air and its cooling effect upon the water contained in the water tubes of the radiator.

Having thus described my invention, it is 20 obvious that various immaterial modifications may be made in the same without departing from the spirit of my invention; hence, I do not wish to be understood as limiting myself to the exact form, construction, arrangement and combination of parts herein shown and described, or uses mentioned.

What I claim as new and desire to secure by Letters Patent is:

- 25 1. In a radiator, a plurality of relatively flat spaced tubes, fins disposed transversely of said tubes, said fins and tubes being secured to each other, members formed in said fins for causing turbulence of air passing through 40 the radiator, said members being disposed at opposed angles in the space between said tubes and arranged adjacent the opposite edges of said tubes and providing means directing air into alternate engagement with the front portion of one tube and the rear portion of an adjacent tube.
- 45 2. In a radiator, a plurality of relatively flat spaced tubes, fins disposed transversely of said tubes, said fins and tubes being secured to each other, members formed in said fins for causing turbulence of air passing through the radiator, said members being disposed at opposed angles in the space between said tubes and being inclined to the vertical and 55 arranged adjacent the opposite edges of said tubes and providing means directing air into alternate engagement with the front portion of one tube and the rear portion of an adjacent tube.
- 60 3. In a radiator, a plurality of relatively flat spaced tubes, fins disposed transversely of said tubes, said fins and tubes being secured to each other, members projecting from the plane of the fin for causing turbulence of air 65 passing through said radiator, said members

being disposed at opposed angles in the space between said tubes and arranged adjacent the opposite edges of said tubes and providing means directing air into alternate engagement with the front portion of one tube and the rear portion of an adjacent tube, said members being arranged relatively to said tubes to allow air passing through the radiator to engage the side faces of adjacent tubes.

In witness whereof, I hereunto subscribe 75 my name this 22nd day of May, A. D. 1929.

ARTHUR B. MODINE.
